DESIGN FOR A COMBINED STORAGE AND DISPLAY CASE OR THE LIKE

Chauncey V. Hill, Trenton, N. J., assignor to C.
V. Hill & Company, Incorporated, Trenton,
N. J., a corporation of New Jersey

Application October 14, 1938, Serial No. 80,451

Term of patent 14 years

To all whom it may concern:

Be it known that I, Chauncey V. Hill, a citizen of the United States, residing at Trenton, in the county of Mercer and State of New Jersey, have invented a new, original, and ornamental Design for a Combined Storage and Display Case or the like, of which the following is a specification, reference being had to the accompanying drawing, forming a part thereof.

Fig. 1 is a front perspective view of a combined storage and display case or the like embodying my design.

Fig. 2 is a top plan view of the combined storage and display case illustrated in Fig. 1.

Fig. 3 is an end view of the combined storage and display case illustrated in Fig. 1 as seen from the right thereof, and

Fig. 4 is an end view of the combined storage

and display case illustrated in Fig. 1 as seen from the left thereof.

The design consists of a combined storage and display case or the like, having a display portion, the upper part of which has a substantially flat top and presents a rearwardly sloping front face with a glass panel therein and an adjacent storage portion having a substantially flat top located below the top of said display portion, the upper part of said storage portion presenting an inclined front face lying substantially in the same plane as the inclined front face of the upper part of said display portion of the case, all as shown.

I claim:

The ornamental design for a combined storage and display case or the like, substantially as shown and described.

CHAUNCEY V. HILL.
